UNITED STATES PATENT OFFICE

IRVING BREGER, OF EVANSTON, ILLINOIS, ASSIGNOR OF ONE-HALF TO WILLIAM H. FETRIDGE, OF EVANSTON, ILLINOIS

DESIGN FOR A WATCH DIAL

Application filed December 9, 1929. Serial No. 33,708. Term of patent 7 years.

To all whom it may concern:

Be it known that I, IRVING BREGER, a citizen of the United States, residing at Evanston, in the county of Cook, State of Illinois, have invented a new, original, and ornamental Design for Watch Dials, of which the following is a specification, reference being had to the accompanying drawing, forming a part thereof,

The figure is a face view of a watch showing my new design.

The arms and hands of the figure which constitutes my novel design are carried by the hour hand and minute hand of the watch while the remaining parts of the figure are applied to the dial plate.

I claim:

The ornamental design for a watch dial substantially as shown and described.

IRVING BREGER.
